UNITED STATES PATENT OFFICE

JOEL LUND, OF SAN FRANCISCO, CALIFORNIA; ANDREW LUND ADMINISTRATOR OF
SAID JOEL LUND, DECEASED

BENCH PLANE

Application filed March 31, 1926, Serial No. 98,689. Renewed August 20, 1928.

This invention relates to improvements in bench planes and resides in the provision of a strong, durable and efficient single bit plane which will be simple as to construction and 5 comparatively inexpensive, yet easy to operate and reliable in use.

One of the objects of the invention is to provide a single bit plane of the character described in which the bit and its associated 10 parts may be more quickly, easily and accurately adjusted than is possible with planes such as heretofore constructed.

Another object of the invention is to provide a means for adjusting the chip breaker 15 which may be readily, easily and accurately operated to best adapt the plane for effective use in working with hard and knotty woods, the said adjusting means being located in a convenient and readily accessible position.

20 A further object of the invention is to provide an assemblage of the bit, chip breaker and operating means therefor, in a compact form whereby the adjusting means may be readily and easily operated and the balance 25 of the plane is improved as well as the general efficiency thereof.

20 A further object is to provide an arrangement of the bit, chip breaker and adjusting mechanisms associated therewith such that 30 the plane may be readily and easily assembled and disassembled.

With the above mentioned and other objects in view, the invention consists in the novel construction and combination of parts 35 hereinafter described, illustrated in the accompanying drawing, and set forth in the claims hereto appended, it being understood that various changes in the form, proportion, 40 size and minor details of construction within the scope of the claims may be resorted to without departing from the spirit or sacrificing any of the advantages of the invention.

Referring to the drawing:

45 Fig. 1 represents a longitudinal sectional

view of a plane constructed in accordance with my invention.

Fig. 2 represents a top plan view of the plane of my invention.

Fig. 3 is a top plan view of the bit and chip breaker assembly as when laid flat. 50

Fig. 4 represents a front elevation of the bit adjusting lever.

Fig. 5 represents a perspective view of the adjusting sleeve and yoke which is operatively associated with the lever. 55

In the embodiment of the invention shown in the accompanying drawing, the plane body 1 is provided at its terminals with the usual hand grips 2 and 3 and between its ends with the usual bit slot 4 extending transversely of the body. Rearwardly of this slot and extending upwardly between the flanges 5 on the body is a web or frog portion generally designated 6, which portion presents an inclined surface on which the bit 7 is slidably supported so that the cutting edge 8 of the bit is disposed in the slot 4. 60

To provide for the adjustment of the bit to true cutting edge with the bottom of the plane, the frog 6 at its upper portion is countersunk as at 9 to receive a circular disk 10 mounted on a central screw pivot 11 and engaged against the under side of the bit. An adjusting lever 12, preferably formed integral with the disk 10, extends outwardly from the disk beneath the bit. A screw 13 is mounted on the disk 10 to one side of the center pivot 11 and its head slidably engages in a longitudinally extending recess 14 formed 80 in the under side of the bit. On moving the lever back and forth, the head of the screw engaging in the recess 14 causes the bit to be shifted in such manner that the cutting edge thereof may be disposed in proper alignment 85 with the bottom of the bit.

To provide for longitudinal adjustment of the bit to regulate the depth of the planing or cutting action, there is provided and adjusting lever 15 mounted in a recess or open- 90

ing 16 provided in the web or frog portion 6. This lever is pivoted on a transversely extending pin 17 having its ends secured to the flanges 5. The upper end of the lever is engaged in one of several spaced openings 18 provided in the bit. On rocking of the lever, the bit will be lowered or raised dependent upon the direction of the movement of the lever. The lower part of the lever is bifurcated and an internally screw threaded sleeve 19 engages in the bifurcation of the lever and supports a yoke 20 in which the lower rounded end 21 of the lever is slidably engaged. An adjusting screw 22 is extended through the sleeve with its lower end 10 extended into a bore 23 provided in the lower part of the web. The lower end of the screw is provided with a head 24 which engages the lower end of a sleeve 25 removably held 15 in the bore by a set screw 26. In this way the screw is held against withdrawal and longitudinal movement and may rotate freely as is necessary to move the sleeve 19 back and forth. On the outer end of the screw 20 is a knurled head 27 so disposed that it may be readily grasped to effect the turning of the screw. On turning the screw in a clockwise direction, the sleeve 19 and yoke 20 are moved upward and rearward and as said yoke engages with the rounded lower end 21 of the lever, said lever will be rocked so that the upper end thereof is moved downwardly. As this end of the lever is engaged in the opening 18 of the bit, such movement thereof will 25 push the bit downward. Turning of the screw in the opposite direction will retract the bit or lift it. But a slight movement of the screw is necessary to change the position of the cutting edge of the bit and by this 30 mechanism the adjustment of the bit may be quickly, easily and accurately effected. As the yoke 20 is moved upward or downward with the sleeve, it is free to slide relative to the rounded end 21 of the lever while maintaining the proper engagement of the lever necessary to effect the rocking thereof with each minute turning of the screw to thereby produce adjustment of the bit. Likewise the upper end of the lever is arranged so as to 35 provide for free engagement thereof in the opening 18 while maintaining the proper engagement of the bit necessary to secure accuracy of adjustment. This adjusting means is accurate and reliable in operation and subject to being readily and easily assembled and disassembled.

The chip breaker 28 is mounted upon the upper side of the bit and is bowed between its ends so that it engages with the bit at its 40 ends only, thus leaving a space sufficient to permit of the protrusion and free movement of the upper end of the lever 15 through the opening 18 during the adjustment of the bit.

The chip breaker is held in place and adjustment thereof provided for by the combined

clamp and adjusting means, which means generally comprises a clamping plate 29 and an adjusting lever 30. The plate 29 is recessed on its under side between its side edges as at 31 to facilitate the mounting of the lever 30 in place and the proper association of the lever with the chip breaker and plate, although the lower transverse edge of this plate is engaged with the upper side of the chip breaker. A pin 32 extending transversely between and fastened to the flanges 5 engages in a transverse groove 33 provided in the upper side of the clamping plate at a point adjacent the lower edge of the plate. A locking screw 34 is adjustably mounted in the upper part of the plate and arranged to bear against the upper side of the chip breaker so as to press the same firmly upon the bit and to hold the chip breaker and bit in place. This screw and the pin 32 hold the clamp in place. The lever 30 is pivoted at its lower end to a screw 35 turned in the center of a small block 36 engaged with the upper side of the lever and extended into an opening 37 provided in the plate 29. In this connection it will be noted that the block 36 and opening 37 are of rectangular form and the opening is of greater length than the block to permit of adjustment of the block therein. The screw 35 is extended through an opening in the chip breaker with the head thereof engaged against the under side of the chip breaker. The lever 30 is provided between its free end and the pivot point thereof with an eccentric slot 38 in which the lower end of the screw 34 engages.

The screw 34 when tightened presses downward on the chip breaker 28 so that said chip breaker in turn presses against the bit 7 and the chip breaker and bit are in this manner securely held in the desired position. To adjust the chip breaker so that the lower edge thereof is disposed in the proper relation to the cutting edge of the bit, dependent upon the work whether the wood be hard, soft or knotty, in order that the best planing results may be obtained, the lever 30 is moved back and forth. To move the chip breaker downward closer to the lower end of the bit the lever 30 is moved to the left and the eccentric slot 38 engaging with the screw 34 causes the lever, chip breaker and block 36 to be moved downward, the elongated opening 37 permitting this movement of the block. Following the proper adjustment to lower the chip breaker, the set screw 34 is tightened to hold the chip breaker in adjusted position. On moving the lever to the right, the eccentric slot in the lever is such that by engagement with the set screw 34, said lever, chip breaker and the pivot block are moved upwardly.

By this adjusting and locking means, not only is provision made for adjustment of the chip breaker but the locking of the chip

breaker and bit assembly in the proper position is provided for. The adjusting means is such that very accurate and fine adjustments of the chip breaker may be made easily and quickly. The locking mechanism is such that it may be readily unlocked to effect the removal of the chip breaker. It will be noted that this may be effected without disturbing the assembly and adjustment of the bit.

10 The chip breaker is provided approximately centrally of its ends with a lug 28' which engages the bit. This permits a flexing of the chip breaker when the screw 34 is pressed tight against it and at the same time insures a rigidity of the assembly sufficient to prevent chattering of the bit.

I claim:

1. A plane comprising a body portion having a bit slot therein, a bit adjustably supported upon the body portion and extending through the slot, a chip breaker mounted upon the bit, a lever mounted upon the chip breaker, a fastening extending through the chip breaker and lever and serving as a pivot for the lever, a block mounted upon the fastening, a clamping plate mounted upon the chip breaker and having an opening therein in which said block is slidably engaged, a pin carried by the body portion and engaging the upper side of the clamping plate, and a set screw adjustable in said clamping plate and engaged with the chip breaker, said lever having a slot extending eccentrically with relation to the pivot therefor, through which slot the set screw extends.

2. A plane comprising a body portion having a bit slot therein; a bit adjustably supported upon the body portion and extending thru the slot; a chip breaker mounted upon the bit; a lever pivotally mounted on said chip breaker; a clamping plate held stationary relatively to the body, said lever having a slot extending eccentrically with relation to the pivot thereof; and clamping means movably secured in said clamping plate and engaging said eccentric slot so as to allow the axial adjustment of the chip breaker by the pivotal movement of said lever.

3. A plane comprising a body portion having a bit slot therein; a bit adjustably supported upon the body portion and extending thru the slot; a chip breaker mounted upon the bit; a lever pivotally mounted on said chip breaker; a clamping plate held stationary relatively to the body; said lever having a slot extending eccentrically with relation to the pivot thereof; clamping means movably secured in said clamping plate and engaging said eccentric slot so as to allow the axial adjustment of the chip breaker by the pivotal movement of said lever; and a block mounted over the pivot of the lever, said clamping plate having an opening therein in which said block is slidably engaged.

4. A plane comprising a body portion hav-

ing a bit slot therein; a bit adjustably supported upon the body portion and extending thru the slot; a chip breaker mounted upon the bit; a lever pivotally mounted on said chip breaker; a clamping plate held stationary relatively to the body, said lever having a slot extending eccentrically with relation to the pivot thereof; and a clamping screw adjustable in said clamping plate and engaged with said chip breaker, said screw extending thru said slot so as to allow adjustment of the chip breaker relatively to the bit by the pivotal movement of said lever.
